POLYPHASE IMPEDANCE DROP COMPENSATOR

Edwin L. Harder, Forest Hills, Pa., assignor to Westinghouse Electric & Manufacturing Company, East Pittsburgh, Pa., a corporation of Pennsylvania

Application December 13, 1935, Serial No. 54,255

5 Claims. (Cl. 172—237)

My invention relates to alternating-current impedance drop compensators, and particularly to such compensators as used in connection with power transformers to derive high-voltage quantities from the low-voltage circuits of the

5 transformers. Such compensators commonly operate to produce compensating effects equivalent in magnitude to impedance effects of the transformers but opposite in sign, which are added to the low-voltage quantities of the transformers to reproduce variables existing on the high-voltage sides of the transformers. If the transformer connections are such that phase voltages and 10 phase currents are carried through the transformation without combinations between phases, the ordinary methods of compensation are directly applicable. However, transformer connections are frequently utilized which result in 15 a different system of secondary polyphase variables because of combinations of phase quantities. In such applications, quantities which are present as components of a single primary variable, usually appear as components of a number 20 of secondary variables, and the duplication of primary variables by compensation methods is ordinarily not practical because of the excessive number of instrument transformers required. I have found, however, that by utilizing 25 the symmetrical impedance relationships which can be obtained in commercial transformer installations, high-voltage quantities may be duplicated from the low-voltage transformer circuits by means of comparatively simple instrument 30 transformer apparatus, and with comparatively small error.

It is accordingly an object of my invention to provide a novel method of and apparatus for impedance drop compensation which will be applicable to polyphase transformer apparatus of the class in which a combination of phase quantities or other change of polyphase dimensions accompanies the transformation.

40 Other objects of my invention will become evident from the following detailed description taken in conjunction with the accompanying drawing, in which

45 Figure 1 is a diagrammatic view of a polyphase transformer and impedance drop compensator embodying my invention.

50 Fig. 2 is a vector diagram showing the relationship of voltages in the transformer bank of Fig. 1.

55 Fig. 3 is a diagrammatic view of a modified

potential transformer arrangement for use in the circuit of Fig. 1, and

Fig. 4 is a diagrammatic view of a simplified impedance drop compensator which may be used in the practice of the invention.

Referring to Fig. 1 in detail, a polyphase high-voltage circuit 1 is connected to a polyphase low-voltage circuit 2 by means of a transformer 3, shown as having star-connected high-voltage windings 4 with neutral ungrounded and delta-connected low-voltage windings 5. The high-voltage windings 4 may be provided with a tap-changing device as indicated diagrammatically at 6.

The transformer 3 may be any suitable form 15 of stationary induction apparatus capable of transforming polyphase power, such as a single polyphase transformer or a bank of single-phase transformers. It is essential, however, that the leakage impedance, on both primary 20 and secondary sides, have substantially the same value as to magnitude and phase angle, in all phases. It is also desirable that the mutual impedance between primary windings and secondary windings be similarly symmetrical in all 25 phases, although some variation of mutual impedance may be permitted without serious error.

A two-element power responsive device such as a wattmeter 7 is provided for measuring a polyphase power quantity, such as the total real 30 power flow, of the circuit 1. The wattmeter 7 is provided with the usual current coils 8 connected to be energized in accordance with phase currents of the high-voltage circuit by means of current transformers 10. The voltage or potential coils 9 of the wattmeter 7 are connected to be energized from the low-voltage circuit 2 by means of a pair of potential transformers 12 and 35 impedance drop compensators 13.

The potential transformers 12 are each preferably so constructed as to produce two secondary voltage components of equal magnitude and to provide simultaneous adjustment of the ratios of these components to the voltage impressed on the potential transformer primary windings. For this purpose, I preferably provide a mid-tap 45 15 on the secondary winding of each potential transformer 12 and adjustable end-taps 16 on the primary windings. It will be obvious, however, that other transformer arrangements having an equivalent function may be used.

The compensators 13 may be of any suitable type, one example of which is disclosed in my co-pending application Serial No. 52,121, filed No- 55

vember 29, 1935, and assigned to the Westinghouse Electric & Manufacturing Company. Such compensators comprise a mutual reactance section 18, consisting of two windings on a common core (not shown), and a mutual resistance section comprising a resistor 20 and a low-voltage auxiliary potential transformer 21. The adjustments of the reactance section 18 and resistor 20 may be similar to those disclosed in the above-mentioned application but for simplicity have been omitted from the present drawing.

The compensators 13 are energized in accordance with line-currents of the low-voltage circuit 2 by means of current transformers 22, and serve to introduce voltages in the secondary circuits of the potential transformers 12 proportional to the voltages consumed by the leakage impedances of the power transformer 3, as explained in my co-pending application mentioned above.

The operation of the above described apparatus may best be understood by considering the circuit analytically. In the following, capital letters are used to denote complex or vector quantities and lower case letters are used as subscripts. The conjugate of any vector quantity is denoted by the corresponding capital letter surmounted by a circumflex accent. Scalar quantities are denoted by a capital letter surmounted by a bar. To simplify the equations, it is assumed that the ratio of each star-connected primary winding of the transformer 3 to the corresponding delta-connected secondary winding is 1:1.

Let

- 35 $E_a' \quad E_b' \quad E_c'$ = line-to-line voltages of circuit 1.
 $E_a'' \quad E_b'' \quad E_c''$ = line-to-neutral voltages of circuit 1.
40 $I_a' \quad I_b' \quad I_c'$ = phase currents of circuit 1.
 $I_a \quad I_b \quad I_c$ = phase currents of circuit 2.
45 $I_a'' \quad I_b'' \quad I_c''$ = currents in the delta-connected windings of transformer 3.
50 $E_a \quad E_b \quad E_c$ = line-to-line voltages of circuit 2.
 P = total power flow in circuit 1.
55 Z = equivalent total leakage impedance of each phase of transformer 3, considered from delta side and assumed the same for all phases.
 Z_s = secondary leakage impedance, or the part of Z caused by the transformer secondary windings only, assumed the same for all phases.
60 Z_x = the exciting impedance, or mutual impedance between primary and secondary windings of each phase of transformer 3, assumed the same for all phases.

As the neutral point of the star-connected winding 4 is ungrounded, the high-voltage circuit 1 is three-phase three-wire, and the total power flow therein may be measured as the sum of the conjugate products of the currents in any two phase conductors and the corresponding voltages 75 of the two conductors with reference to the re-

maining conductor. Taking the *b*-phase conductor as reference, the total power flow is P where

$$P + jQ = E_a' I_a' + E_c' I_c' \quad \dots \quad (1)$$

Neglecting exciting current in the transformer 3, the primary voltages are equal to the sum of the secondary voltages and the corresponding leakage impedance drops:

$$\begin{aligned} E_a'' &= E_a + I_a'' Z \\ E_b'' &= E_b + I_b'' Z \\ E_c'' &= E_c + I_c'' Z \end{aligned} \quad \dots \quad (2)$$

Because of the star-delta voltage relationship at the primary windings 4 of transformer 3 (see Fig. 2) the voltages E_a' and E_c' may be represented as

$$\begin{aligned} E_a' &= E_c'' - E_b'' \\ E_c' &= E_b'' - E_a'' \end{aligned} \quad \dots \quad (3)$$

Substituting (2) in (3)

$$\begin{aligned} E_a' &= E_c + I_c'' Z - E_b - I_b'' Z \\ E_c' &= E_b + I_b'' Z - E_a - I_a'' Z \end{aligned} \quad \dots \quad (4)$$

The Equations (4) express the high-voltage quantities E_a' and E_c' in terms of three voltages E_a , E_b and E_c of the low-voltage circuit 2, and the three delta currents I''_a , I''_b and I''_c circulating in the secondary windings 5. As the delta currents cannot be conveniently measured without special connections, it is preferable to substitute the secondary phase currents for the delta currents. Also, as the circuit 2 is three-phase, three-wire, one secondary current and one secondary voltage may be eliminated from Equations (4).

The relationship of currents at the junctions of the delta is

$$\begin{aligned} I_c &= I_a'' - I_b'' \\ I_a &= I_b'' - I_c'' \end{aligned} \quad \dots \quad (5)$$

The relationship of voltages at the delta-connected windings 5 is, as shown vectorially in Fig. 2,

$$E_b = -E_a - E_c \quad \dots \quad (6)$$

Substituting (5) and (6) in (4) and rearranging

$$\begin{aligned} E_a' &= 2E_c + E_a - I_a Z \\ E_c' &= -2E_a - E_c - I_c Z \end{aligned} \quad \dots \quad (7)$$

Equations (7) show that the phase-to-phase voltages of circuit 1 may be expressed as functions of two secondary phase-to-phase voltages and a secondary phase current of circuit 2. However, as there is a circuit around the delta which could carry a residual or zero-sequence current component, the polyphase quantities of circuit 2 can be completely expressed by these variables only if the flow of zero-sequence current is prevented. It is therefore necessary to establish that no zero sequence current circulates in the delta for the above relationships to hold rigidly.

It will be noted that the terms $I_a Z$ and $I_c Z$ of Equations (7) above are each derived from a plurality of terms of Equations (4) and appear as single terms in (7) only because the same value of leakage impedance Z has been assumed for all phases. As the terms $I_a Z$ and $I_c Z$ represent compensating voltages introduced by the compensators 13, it will be apparent that symmetrical leakage impedances Z of the power transformer 3 are necessary for accurate compensation in accordance with the principle of the invention.

The voltages acting around the delta consist entirely of mutual impedance drops derived from the primary phase currents, and the self-impedance drops of delta currents in the secondary

leakage impedances Z_s . The voltage equation of the delta, accordingly, is

$$\left. \begin{aligned} (I_a' + I_b' + I_c') Z_x + (I_a'' + I_b'' + I_c'') \\ (Z_s + Z_x) = 0 \end{aligned} \right\} \quad \dots \quad (8)$$

5 However as the high-voltage circuit is assumed three-phase, three-wire,

$$I_a' + I_b' + I_c' = 0 \quad \dots \quad (9)$$

10 Substituting (9) in (8) and factoring

$$I_a'' + I_b'' + I_c'' = 0 \quad \dots \quad (10)$$

15 As the delta currents add to zero, there is no circulating current in the delta which could disturb the relationships stated above. It will be noted that Equation (8) holds only if the exciting impedance Z_x is symmetrical in all phases and the secondary leakage impedance Z_s is similarly symmetrical. It may also be shown that symmetrical 20 primary leakage impedance of the transformer is necessary to eliminate any residual component of the primary star voltages with reference to the junction point of primary windings 4, in order to provide power measurements rigidly following 25 Equation (1).

Fig. 3 shows a modified potential transformer arrangement which may be substituted for the potential transformers 12 of Fig. 1. In Fig. 3 the potential transformers 25 are provided with two 30 secondary windings 26 and 27, one having twice the number of turns of the other. By proper connection of the windings 26 and 27, the two output potential circuits may be separately grounded, as may be desirable for energizing star-connected 35 measuring devices or for other reasons.

Fig. 4 shows an alternative construction of impedance drop compensator which may be substituted for the compensators 13 of Fig. 1. In the Fig. 4 construction, a parallel connection of 40 the reactance section 31 and the resistor 32 is employed, eliminating the necessity for an auxiliary potential transformer, such as the transformer 21 of Fig. 1.

I do not intend that the present invention shall 45 be restricted to the specific structural details, arrangement of parts or circuit connections herein set forth, as various modifications thereof may be effected without departing from the spirit and scope of my invention. I desire, therefore, that 50 only such limitations shall be imposed as are indicated in the appended claims.

I claim as my invention:

1. In an alternating-current system, a pair of 55 polyphase circuits, translating means including a closed circuit connected to all phases of a first of said polyphase circuits and having substantially uniform leakage impedance between all phases thereof, said closed circuit having substantially uniform mutual impedance to all phases of the 60 second of said polyphase circuits, and means for deriving voltages of one of said polyphase circuits from the other thereof comprising phase-shifting means for correcting the shift of phase voltages in said translating means, and compensating means for correcting the leakage impedance voltage loss in said translating means.

2. In an alternating-current system, a pair of 65 three-phase circuits, translating means including

a delta circuit connected to all phases of a first of said three-phase circuits and having substantially uniform leakage impedance between all phases thereof, said delta circuit having substantially uniform mutual impedance to all phases of the second of said three-phase circuits, and means for deriving phase voltages of one of said three-phase circuits from the other thereof comprising means for combining components of delta voltages of said other circuit in such manner as to correct the shift of voltages in said translating means, and compensating means for correcting the leakage impedance voltage loss in said translating means.

3. In an alternating-current system, a high-voltage three-phase three-wire circuit, a low-voltage three-phase three-wire circuit, transformer means including delta-connected windings connected to said low-voltage circuits and star-connected windings connected to said high-voltage circuit, said transformer means having substantially uniform leakage impedance in said delta-connected windings and substantially uniform exciting impedance in 25 all phases, and means for deriving voltages of said high-voltage circuit from said low-voltage circuit comprising means for dividing two delta voltages of said low-voltage circuit in equal components and for adding said components to undivided delta voltages in such manner as to substantially duplicate the phase voltages of said high-voltage circuit as to phase position, and compensating means for correcting the leakage impedance voltage loss in said translating means. 35

4. In an alternating-current system, a pair of three-phase three-wire circuits, transformer means having star-connected windings connected to one of said circuits and delta-connected windings connected to the other of said circuits, said 40 transformer means having constants such as to substantially exclude the circulation of zero sequence current in said delta-connected windings, and means for deriving voltages of one of said three-phase circuits from the other of said circuits including compensating impedances and 45 means for energizing said compensating impedances in accordance with current quantities derived from the phase currents of said other of said circuits. 50

5. In an alternating-current system, a pair of three-phase three-wire circuits, transformer means having star-connected windings connected to one of said circuits and delta-connected windings connected to the other of said circuits, said 55 transformer means having constants such as to substantially exclude the circulation of zero sequence current in said delta-connected windings and having substantially uniform leakage impedance in all phases, and means for deriving voltages of one of said three-phase circuits from the other of said circuits, including compensating impedances, and means for energizing said compensating impedance means in accordance with current quantities derived from two phase 60 currents of said other of said circuits. 65

EDWIN L. HARDER.
